UNITED STATES PATENT OFFICE.

MAX STURM, JR., OF KEYPORT, NEW JERSEY.

CARGO BINDER.

Application filed January 2, 1925. Serial No. 206.

To all whom it may concern:

Be it known that I, MAX STURM, Jr., a citizen of the United States, residing at Keyport, in the county of Monmouth and State of New Jersey, have invented new and useful Improvements in Cargo Binders, of which the following is a specification.

This invention relates to braces for holding articles against movement when loaded in freight cars and the like, the general object of the invention being to provide means whereby each brace can be wedged crosswise in the car.

Another object of the invention is to provide detachable means on the braces for engaging the wheels of a motor vehicle or the like.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a horizontal sectional view through a car showing the invention as being used to hold a motor vehicle against movement.

Figure 2 is a section on line 2—2 of Figure 1.

Figure 3 is a section on line 3—3 of Figure 1.

Figure 4 is a section on line 4—4 of Figure 1.

Figure 5 is a perspective view showing one end of one of the braces with the wedge plate thereon.

Figure 6 is an end view of one of the threaded members.

Figure 7 is a view showing a slight modification.

As shown in these views, the brace members 1 are made in the form of rods which extend transversely across the car, one end of each rod having a projection 2 thereon which is rounded and the other end having a threaded socket therein to receive a threaded shaft 3 which is formed with a rounded end 4 and said shaft is provided with a nut-shaped head 5 which is located between the threaded part and the rounded part 4 and which is provided with holes 6 so that a

rod can be inserted for holding a handle for turning the shaft. The rounded ends of the parts 2 and 4 are adapted to engage rounded recesses 7 formed in plates 8 which are provided with spurs 9 for penetrating the side walls of a car A. Thus when the shaft 3 of each brace member is rotated by its head 5 the brace will be lengthened so that the plates 8 will be jammed against the side walls of the car with the spurs entering the walls so that the brace will be firmly supported transversely of the car. Thus the braces can be used for forming partitions in a car and thus prevent the cargo or contents of the car from sliding about therein. Figure 1 shows the braces being used to prevent the chassis of a motor vehicle, shown at C, from moving about in the car. In this case a pair of arms 11 are placed on each brace with the outer end of each arm having a curved part 12 which is provided with a curved channel therein for receiving a portion of the tire of the wheel of the vehicle. Each arm is provided with an opening for receiving a part of the brace and the arm is fastened in adjusted position on the brace by a set bolt 13. Thus when the braces are put in position with the channel shaped parts of the arms engaging the wheels of a vehicle, as shown in Figure 1, the vehicle is held against movement in the car.

In order to strengthen the braces I may provide them with stays 14, the outer ends of each set of stays being hooked into openings 15 made in the plates 8 and their inner ends are pivoted to a bracket 16 which has a socket therein for receiving one end of a threaded shaft 17, the threaded part of which engages a threaded socket in an arm 18 which has an opening therein through which a brace member is passed. The shaft 17 is provided with a head 19 so that the shaft can be turned to tighten the stays.

Figure 7 shows a modification in which the brace member is formed of two sections 1' and 1'' with one section having a threaded socket therein for receiving the threaded part of the other section.

From the foregoing it will be seen that I have provided braces which can be wedged transversely in a freight car or other vehicle to support the cargo against movement. The braces can be easily and quickly set up and taken down without damage to the car or its contents.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

- 10 1. A device of the class described comprising a rod having a threaded socket in one end thereof, a threaded member engaging said socket, said member and rod each having its outer end rounded, plates having recesses therein for receiving the rounded ends, a nut-shaped head on the threaded member for permitting it to be turned, stay rods detachably connected with the plates, a part to which the inner ends of the stay rods are connected and means for adjustably connecting said part to the rod.
- 15 2. A device of the class described comprising a rod having a threaded socket in one end thereof, a threaded member engaging said socket, said member and rod
- 20 25

each having its outer end rounded, plates having recesses therein for receiving the rounded ends, a nut-shaped head on the threaded member for permitting it to be turned, stay rods detachably connected with the plates, a part to which the inner ends of the stay rods are connected, means for adjustably connecting said part to the rod, such means comprising an arm removably attached to the rod and having a threaded 35 socket, a threaded member engaging the socket and the part to which the stay rods are attached and a nut-like head on the threaded member.

3. A device of the class described comprising a telescopic member, plates at the ends of the member, means for lengthening the member to wedge the plates against the walls of a carrier, an arm carried by said member and a curved part on the outer 45 end of the arm having a channel therein for receiving portion of a wheel.

In testimony whereof I affix my signature.

MAX STURM, JR.
